CONDIMENT DISPENSER

Earl W. Clark, Stuart, Fla.

Application March 27, 1952, Serial No. 278,825

4 Claims. (Cl. 222—190)

1

This invention relates to improvements in dispensers for finely divided materials such as ordinary table salt and the like which have a relatively strong tendency to absorb any moisture which they may contact and also to absorb moisture from damp air. This invention relates more specifically to a dispenser so constructed that the interior surfaces of same, excepting ordinarily the stopper, comprise a material which has a relatively great affinity for and will quickly absorb any applied or contacting moisture or any moisture which condenses thereon.

In ordinary salt dispensers the interior surfaces comprise or are ordinarily made of materials such as glass, plastic or china which do not absorb applied moisture, and I find that during periods of dampness the interior surfaces so made are very liable to become dampened by moisture in the air within the dispenser condensing thereon. This condensed moisture is absorbed by the salt when the dispenser is inverted and some salt will adhere to the dampened surfaces and some will fall back and in turn dampen additional salt within the container. Sometimes the neck of the bottle or container becomes completely clogged by adhering salt and I find also that the dispensing openings may become clogged if the material comprising the dispensing head is made up of or has adjacent thereto a material which does not readily absorb moisture.

My invention is particularly directed to a construction which is adapted to overcome the difficulties caused by moisture condensing out of the atmosphere within the dispenser and on to the interior surfaces of the container during periods when the atmosphere is damp and subject to temperature changes. I accomplish this result by constructing the entire interior surfaces of the dispenser, excepting ordinarily the stopper as mentioned previously, of a material which has a relatively low degree of heat conductivity and which also has fairly good hygroscopic or moisture absorbing qualities. Any moisture which may condense from the air within the dispenser and on to the interior surfaces of my herein described dispensers during periods of damp air and changing temperature is quickly absorbed into the interior thereof where salt cannot ordinarily contact it and hence salt within the dispenser will not be dampened to any appreciable extent by this absorbed moisture. Further, I find that this absorbed moisture will be largely dissipated during periods of dry weather and that my dispenser will give long periods of trouble free operation.

2

Other objects and advantages of my invention will be apparent from the accompanying drawing and the following detailed description.

In the drawing:

5 Fig. 1 is a sectional elevation of a dispenser, it also indicates by dotted lines the mold and core used in forming same.

Fig. 2 is a side elevation of a dispenser.

10 Fig. 3 is a fragmentary sectional elevation of a dispenser showing a modified form of stopper.

Fig. 4 is similar to Fig. 3, but shows a different stopper.

Fig. 5 is a fragmentary sectional elevation of a dispenser showing another type of stopper.

15 Fig. 6 is a fragmentary sectional elevational of a dispenser having an outer envelope or covering.

Fig. 7 is similar to Fig. 6, but the outer envelope or covering is omitted on the top portion of dispenser.

20 Fig. 8 is a sectional elevation of a dispenser having an outer shell or envelope lined with a hygroscopic material.

Referring in detail to the drawing wherein in the various figures the same numbers designate 25 identical or similar parts, in Fig. 1, 1 indicates the body of the dispenser. The material which I use in forming this body has the property of being molded or cast while in a plastic condition and also of setting from a plastic to a solid state and forming a unitary hygroscopic body. I generally use plaster of Paris for this material as I find that plaster of Paris may be mixed with sufficient water so that it may readily be poured

30 into a mold and that a mixture so made will set fairly quickly and form a solid body that has a fair amount of structural strength and also is sufficiently hygroscopic to be used in any part of a salt dispenser. I pour the wetted plaster of Paris into the mold 19 in Fig. 1 which is indicated by dotted lines while the mold 19 is in an inverted position. I next agitate this material to drive out any air bubbles and then insert the core 20, shown also by dotted lines, to the position shown and hold same in place until the 35 plastic plaster of Paris has set sufficiently to hold the core 20. Inside of an hour the mold 19 and core 20 may be removed as the plaster of Paris will have set within this time into a solid substance which is called gypsum.

Sometimes I insert the tapered core 20 only part way into the mold 19 and then drill out or otherwise remove or cut out the rest of the interior. I also sometimes do not use the core 20, but drill out the whole cavity. This can very readily be done as gypsum drills and carves easily. When the freshly cast body is removed from the mold it

is very damp and it must be dried thoroughly before using same as a dispenser. For drying the body 1 generally use hot air or gas fumes although the body will dry out in dry air. I make the inside of the body tapered as shown at 1a for ease of molding, to increase capacity and to provide a tapered seat for the cork stopper 3. A tapered seat for the stopper has several advantages. It reduces wear on the gypsum body where the stopper contacts same and also reduces wear on the stopper. Further, the stopper may be pushed tightly in place and still be removed relatively easily. If wear does occur in the stopper seat the stopper is made tight by merely pushing it in a little further. In Fig. 7, 22 indicates a coating for the inside of the dispenser where the stopper contacts the dispenser body to prevent wear of the gypsum by the stopper at this point. 2 is the dispensing opening and 1b is a tapered portion to facilitate prying out stopper 3.

In molding body 1 as shown in Fig. 1, I have used for my experimental models plastic cups 19 and plastic cup shaped cores 20 which have substantially the same taper as ordinary corks. In some of these molds 19 I drill a one-half inch hole 21 which I cover with tape before pouring in the wetted plaster of Paris. When the plaster of Paris hardens I use a short piece of wooden dowel material and place one end in hole 21 and then strike the dowel with a hammer to drive the body 1 from mold 19. I support the inverted mold 19 on two square pieces of steel, which are well known and are not shown, so placed that the body 1 will not touch same as it is forced out of mold 19. The body 1 can also be removed from mold 19 where hole 21 is not provided by inverting the filled mold and bringing the edges of or rim of the mold 19 down sharply on to the above mentioned square pieces of steel. I prefer to remove the body 1 from the mold 19 before drilling or cutting out the whole of the inside as otherwise the head might be broken in when driving the body 1 out of mold 19. I have also used a light or thin plastic mold 19 and left the mold on the body permanently as I find that it is advisable to cover the body 1 with a moisture-proof envelope or covering as shown by 13 in Fig. 6 or by a partial covering as shown by 13a in Fig. 7. The reasons for the covering will be explained later.

Fig. 2 in side elevation a completed dispenser having a moisture-proof envelope on the outside thereof.

In Fig. 3, 1 is the hygroscopic dispenser body as in Fig. 1 and a hygroscopic stopper 4 with a pull cord 5 for removing the stopper.

In Fig. 4 a cork stopper 6 with pull cord 7 is shown. The stopper 6 is drilled for cord 7 and the upper end is machined out so as to make a pocket 5a for the bent-over cord ends and this pocket is filled with a syrupy mixture of plaster of Paris and water to anchor the cord to the stopper.

In Fig. 5, 9 represents the hygroscopic body and 10 is hygroscopic plug with a removable cork stopper fitted therein. Plug 10 before inserting in place in 9 is coated with a thin slurry of plaster of Paris and is thus firmly attached to 9 at 12. 10a indicates a beveled or recessed portion to permit the stopper to be pried loose. I find that an ordinary teaspoon as indicated by dotted lines 18 in Fig. 7 is a very satisfactory tool for removing cork stoppers where a pull cord is not provided.

Figs. 6 and 7 are enlarged partial sectional elevations of the body 1 shown in Fig. 1, but with the addition of a water-proof envelope 13 covering the whole of the exterior surface of the body 1 as shown in Fig. 6 and a water-proof envelope 13a covering only part of the body 1 as shown in Fig. 7. The water-proof envelopes 13 and 13a can also be made by painting a good quality of enamel paint on the exterior surfaces of body 1. Whether one uses a preformed plastic envelope or paints same on can be decided on the basis of relative availability and costs. In Figs. 6 and 7, 2 is the dispensing opening as in Fig. 1. In Fig. 7 the water-proof envelope is carried up inside the body 1 as indicated by 22 where the cork stopper contacts same to reduce wear on the body at this point.

I find by tests and experiments, wherein I placed the various types of dispensers shown on my drawing in an open window having a canopy or metal awning so that the dispensers could not be contacted by falling rain, that if one does not cover the outside of the hygroscopic body 1 with a water-proof envelope salt in the dispenser soon becomes damp during a 12 to 24 hour period such as accompanies an over-night rain. A dispenser partially covered as by 13a in Fig. 7 will show some dampening of salt within a 24 hour rainy period while a dispenser protected completely by a water-proof envelope 13 as shown in Fig. 6 will show no dampening of the salt within the above period.

In Fig. 8 I show a china envelope 14 coated on the inside with a hygroscopic material 15 such as is used for the dispenser bodies 1 in Fig. 6. 16 is the dispensing opening and 17 is the cork stopper, 14c is the neck of the envelope 14, 14a is the base and 14b is a tapered portion to aid in removing the stopper 17. The hygroscopic coating or lining 15 may be cast in envelope 14 and then partially cored out and the balance machined out as in Fig. 1, or a plastic mixture of plaster of Paris may be poured into the inside of 14 and then by turning 14 around slowly in all directions the coating 15 will be distributed fairly evenly over the inside surfaces of 14 and will harden in a few minutes. A thicker coat may be added by repeating the operation, but this should be done before the previous coat has dried out. The dispensing opening 16 is drilled after the coating 15 has hardened and then the interior of the dispenser must be thoroughly dried out before using.

What I claim is:

1. In combination in a dispenser for finely divided material comprising, a container body having a dispensing passage in the top portion and a filling opening in the bottom portion thereof, said container body comprising a cast and relatively fragile body of hygroscopic material with a dispensing passage formed therein, a water-proof envelope encircling and contacting the said body of hygroscopic material, a closure member comprising a resilient material for closing said filling opening by making sealing contact with said envelope, said envelope at the bottom portion of said body being positioned between said body and said closure member where said closure member makes sealing contact with said envelope, whereby said closure member does not contact and wear said hygroscopic material when being removed and replaced.

2. In combination in a dispenser for finely divided material comprising, a container body having a dispensing passage in the top portion

and a filling opening in the bottom portion thereof, said container body comprising a cast and relatively fragile body of hygroscopic material with said dispensing passage formed therein, a water-proof envelope encircling and contacting the said body of hygroscopic material, a closure member comprising a resilient material for closing said filling opening by making sealing contact with said envelope, said envelope at the bottom portion of said body being turned inwardly to define and shape said filling opening in said hygroscopic body.

3. In combination in a dispenser for finely divided material comprising, a container having a dispensing passage in the top portion and a filling opening in the bottom portion thereof, said container comprising a cast and relatively fragile body of hygroscopic material with said dispensing passage formed therein, a water-proof envelope encircling and contacting said hygroscopic body, a closure member comprising a resilient material for closing said filling opening by making sealing contact with said envelope, said envelope at the bottom portion of said container being positioned between said hygroscopic body and said closure member, whereby said closure member does not contact and wear said hygroscopic material when being re-

10 moved and replaced, and means for retaining said body in said envelope.

4. In combination in a dispenser for finely divided material comprising, a container body having a dispensing passage in the top portion and a filling opening in the bottom portion thereof, said container body comprising a cast and relatively fragile body of hygroscopic material with said dispensing passage formed therein, a water-proof preformed envelope encircling and contacting said body of hygroscopic material, a closure member comprising a resilient material for closing said filling opening by making sealing contact with said envelope, said envelope at the bottom portion of said dispenser being positioned between said body and said closure member, whereby said closure member does not contact and wear said hygroscopic material when being removed and replaced.
